LIQUID DISPENSING CONTAINER

Theodore E. Brown, Chicago, Ill.

Application April 17, 1957, Serial No. 45,764

Term of patent 14 years

(Cl. D2—3)

FIG. 1

FIG. 2

FIG. 3

Fig. 2 is a side elevational view thereof.

Figs. 3 and 4 are top and bottom plan views, respectively, thereof.

I claim:

The ornamental design for a liquid dispensing container, as shown.
